EUGÈNE SCHNEIDER, OF PARIS, FRANCE, ASSIGNOR TO SCHNEIDER & CIE., OF PARIS, FRANCE, A LIMITED JOINT-STOCK COMPANY OF FRANCE.

APPARATUS FOR THE MANUFACTURE OF METAL TUBES BY THE SELF-HOOPING PROCESS.

1,391,010.

Specification of Letters Patent. Patented Sept. 20, 1921.

Original application filed March 31, 1919, Serial No. 286,501. Divided and this application filed November 3, 1920. Serial No. 421,468.

To all whom it may concern:

Be it known that I, EUGÈNE SCHNEIDER, a citizen of the Republic of France, and a resident of Paris, France, have invented new and useful Improvements in Apparatus for the Manufacture of Metal Tubes by the Self-Hooping Process, which invention is fully set forth in the following specification:

This application is a division of my former application filed March 31, 1919, Serial No. 286,501, for an improved process and apparatus for the manufacture of metal tubes of great strength by the "self-hooping" method, which consists in subjecting the interior of the tube to charges of fluid under very high pressure to stress and to condense the metal to shape and to strengthen the same.

The process disclosed in the former application consists, broadly, in subjecting the interior of the tubes to be treated to successive charges of high liquid pressure with a progressive increase in the area of application of each successive charge, so that the area of application of a succeeding charge includes the area of application of a preceding charge. In the former application are shown and described two constructional forms of the improved apparatus for carrying out the process, and one of said constructional forms constitutes the subject-matter of the present application.

The present constructional form of the improved apparatus comprises a mandrel 35 slidable through a screw-block temporarily seated in an end of the tube to be treated. The mandrel carries at its end entering the tube a piston-like head that is moved, when unrestrained, by the entering fluid-pressure 40 toward the opposite end of the tube, carrying the mandrel with it. A similar head is placed inside of the tube to abut the screw-block to be held stationary thereby, the mandrel being slidable through this stationary head. The movable and stationary heads 45 form an annular chamber between the mandrel and the tube into which fluid-pressure is charged by a conduit in the mandrel leading from a suitable source of supply. The 50 piston-like heads are of such a structure as to prevent leakage from the annular chamber.

During the application of the fluid-pressure the mandrel, and consequently the movable head, is held against movement by a series of sleeves or liners displaceably mounted on that part of the mandrel projecting outside of the screw-block and held by suitable abutments. By successively displacing the sleeves from the mandrel the latter and the movable head are permitted to move into the tube to increase progressively the length of the annular chamber to receive the successive charges of fluid pressure. This progressive increase in the length of the annular chamber increases the area of application of each charge of fluid pressure so that the area of application of a succeeding charge includes the area of application of a preceding charge.

While the apparatus is particularly adapted to the treatment of gun-barrels and will be so described, yet it can be employed in the treatment of other tubular structures in which it is desired to condense and shape the metal adjacent to the bore thereof.

In the drawings, showing the present constructional form of the improved apparatus, Complementary Figs. 1 and 1^a show a longitudinal section of a gun barrel (part of the breech being broken away) with the apparatus applied thereto, the piston-like heads being in a position to confine the annular chamber to the first zone of treatment. Complementary Figs. 2 and 2^a show a similar view with the movable head advanced to confine the annular chamber to the second zone of treatment.

As shown in the drawings, A is the gun barrel to be treated and B is the mandrel 90 entering the bore of the barrel, carrying at its inner end the head J, held on the mandrel by the nut C¹. In entering the barrel the mandrel passes through the screw-block D temporarily turned into the breech of the barrel. Within the barrel and abutting the screw-block is the stationary head J¹ through which the mandrel passes. The heads J and J¹ are of piston-like formation fitting the bore of the barrel and having elastic 100 packings to prevent leakage past the same. The detail construction of these heads is shown in my former Patent 1,331,216, dated Feb. 17, 1920.

The heads J and J^1 form within the barrel an annular chamber into which fluid pressure is charged to stress and to strain the metal to shape and to strengthen the same. The fluid-pressure enters the annular chamber from the conduit b in the mandrel communicating through the pipe E with a suitable source of supply (not shown). The pipe E is provided with an ordinary valve (not shown) so that the flow of fluid-pressure into the annular chamber can be controlled.

The mandrel B is slidable through the screw-block D , but its inward movement is controlled by a series of sleeves F^2 — F^6 displaceably mounted on the mandrel outside of the screw-block. When the sleeves are in place on the mandrel they are interposed between holding abutments formed by the screw-block and the nut C on the outer extremity of the mandrel. When the sleeves are so placed the mandrel is prevented from moving inwardly and the head J is held immovable against the thrust of the fluid-pressure in the annular chamber. As the head J^1 is stationary and the head J held immovable so long as the sleeves remain in place, the application of the fluid-pressure to the wall of the barrel will be confined to the area between the two heads.

To displace the sleeves F^2 — F^6 the nut C is removed from the outer end of the mandrel and the outermost sleeve is slipped off and the nut is replaced. Before the nut is removed the fluid-pressure is cut off from the annular chamber to relieve the pressure on the mandrel and the sleeves. A further provision may be made for displacing the sleeves. Each sleeve may be divided longitudinally, as sleeve F^5 , into halves and the two members are clamped together around the mandrel by the divided bands f joined at their ends by suitable screw-bolts. By removing the screw-bolts the bands can be released and the two members of the sleeve separated and removed from the mandrel without unscrewing the nut C . One advantage of the divided sleeve is that an inner sleeve can be displaced from the mandrel without removing the outer sleeves.

As the thicker wall of the breech of the barrel is required to withstand the greater strains of the discharge, the metal thereof is subjected to repeated applications of the fluid-pressure to increase its powers of resistance. Toward the muzzle of the barrel the number of applications are gradually decreased as resistance requirements gradually lessen.

To facilitate the application of the fluid pressure the barrel is divided into zones Z^1 — Z^6 , diagrammatically indicated, according to the varying thickness in the wall of the barrel. That is, the wall in each zone

is practically of the same thickness throughout and all the metal thereof requires approximately the same treatment. Corresponding to the successive zones Z^2 — Z^6 is the series of sleeves F^2 — F^6 arranged in the same sequence on the mandrel B , preliminary to the operation of the apparatus. The lengths of the respective sleeves are indicated diagrammatically at L^2 — L^6 and correspond to the lengths of the different zones in the same sequence.

The mandrel B , the heads J , J^1 and the screw block D having been mounted in the gun barrel, preliminary to the operation of the apparatus the sleeves F^2 — F^6 are arranged on the mandrel in the order indicated. Fluid-pressure is then admitted to the annular chamber between the heads J , J^1 and the head J is moved into the barrel, carrying the mandrel with it, until the sleeves F^2 — F^6 are crowded together between the nut C and the screw-block D , which will prevent any further movement of the mandrel and the movable head in the barrel. This relative arrangement of the several parts will position the heads J , J^1 to confine the annular chamber to the zone Z^1 , which practically includes the entire breech part of the barrel. The fluid-pressure entering the annular chamber strains and stresses the metal in the wall to shape and to strengthen the same. When the metal has been sufficiently treated the fluid-pressure is cut off from the annular chamber and the sleeve F^2 is removed from the mandrel either by unscrewing the nut C , or by releasing clamping bands f . The displaced sleeve F^2 has a length L^2 corresponding to the length of the zone Z^2 . After the nut C is replaced, if it has been removed, the fluid-pressure is turned on again and the movable head is forced farther into the barrel until the sleeves and the abutments again impinge on each other and stop the movement of the mandrel and the head. This second movement will position the movable head J to include the zone Z^2 within the limits of the annular chamber. The new area of application of fluid-pressure includes the former zone Z^1 and the additional zone Z^2 . The operation is repeated until all the sleeves are displaced and the nut O impinges on the screw-block D . In this final stage of the treatment all the zones of the barrel are included in the area of application of the fluid-pressure.

In the successive applications of fluid-pressure the area treated is progressively increased, the zone of a succeeding application including the zones of all the preceding applications. As the breech is in the first zone, the metal of the same receives an intensified treatment, which imparts to the barrel the greatest strength where it is most required.

This intense treatment progressively lessens toward the muzzle where the least strength is required.

What is claimed is:

5. 1. An apparatus for treating metallic tubes to shape and to strengthen the same comprising means for closing one end of the tube to be treated, means for charging fluid-pressure into the closed end of the tube, a head movable in the tube in advance of the fluid-pressure to confine the latter to a predetermined zone of application, a mandrel entering the tube and carrying the movable head, a series of sleeves slidable on the mandrel outside of the tube to be sequentially displaced from said mandrel, an abutment on the tube to engage one end of the series of sleeves, and a nut on the outer end of the mandrel forming an abutment for the other end of the series of sleeves, said abutments operating to hold the sleeves in place on the mandrel, said sleeves so held operating to hold the mandrel to maintain the head against the thrust of the fluid-pressure, the removal of said nut permitting the release of the sleeves to be displaced by inward movement of the mandrel, the sequential displacement of the sleeves from the mandrel controlling the advance of the movable head and the length of the individual sleeves determining the area of increase in the consecutive applications of fluid-pressure.
2. An apparatus for treating metallic tubes to shape and to strengthen the same, comprising means for closing one end of the tube to be treated, means for charging fluid-pressure into the closed end of the tube, a head movable in the tube in advance of the fluid-pressure to confine the latter to a predetermined zone of application, a mandrel entering the tube and carrying the movable head, and a series of sleeves mounted on the mandrel outside of the tube and sequentially displaceable from the mandrel, said sleeves coöoperating with a holding means and the mandrel to hold the head against the thrust of a fluid-pressure charge, the displacement of the sleeves from the mandrel controlling the advance of the head, the length of the individual sleeves determining the area of increase in the consecutive applications of fluid-pressure.
3. An apparatus for treating metallic tubes to shape and to strengthen the same comprising means for closing one end of the tube to be treated, means for charging fluid-pressure into the closed end of the tube, a head movable in the tube in advance of the fluid-pressure to confine the latter to a predetermined zone of application, a mandrel entering the tube and carrying the movable head, a series of sleeves slidable on the mandrel outside of the tube to be sequentially displaced from the mandrel by the inward movement of the mandrel through the action of the fluid-pressure on the movable head, and means operable to engage the sleeves remaining on the mandrel after the displacement of a sleeve to limit the inward movement of the mandrel and head to the distance determined by the length of the displaced sleeve.
4. An apparatus for treating metallic tubes to shape and to strengthen the same, comprising means for closing one end of the tube to be treated, means for charging fluid-pressure into the closed end of the tube, a head movable in the tube in advance of the fluid-pressure to confine the latter to a predetermined zone of application, a mandrel entering the tube and carrying the movable head, a series of sleeves slidable on the mandrel outside of the tube to be sequentially displaced from said mandrel, an abutment on the tube to engage one end of the series of sleeves, and a nut on the outer end of the mandrel forming an abutment for the other end of the series of sleeves, said abutments operating to hold the sleeves in place on the mandrel, said sleeves so held operating to hold the mandrel to maintain the head against the thrust of the fluid-pressure, the removal of said nut permitting the release of the sleeves to be displaced by inward movement of the mandrel, the sequential displacement of the sleeves from the mandrel controlling the advance of the movable head and the length of the individual sleeves determining the area of increase in the consecutive applications of fluid-pressure.
5. An apparatus for treating metallic tubes to shape and to strengthen the same, comprising a stationary head closing one end of the tube to be treated, a mandrel slidable through the stationary head and entering the tube, a movable head in the tube on the inner end of the mandrel, said heads forming a chamber in the tube, means for changing fluid-pressure into said chamber, and a series of sleeves displaceably mounted on the outer end of the mandrel and interposed between an abutment carried by the tube and a detachable abutment at the outer end of the mandrel, said sleeves and abutments operating to hold the mandrel and movable head against the thrust of fluid-pressure in the chamber, the detachment of the abutment on the outer end of the mandrel permitting sequential displacement of the sleeves from the mandrel with a consequent inward movement of the mandrel and movable head when the chamber is charged with fluid-pressure, the sequential displacement of the sleeves from the mandrel controlling the advance of the movable head and the length of the individual sleeves determining the area of increases in the consecutive applications of the fluid-pressure.
6. An apparatus for treating metallic tubes to shape and to strengthen the same, comprising a screw-block turned into one end of the tube to be treated, a stationary head in the tube abutting the screw-block, a mandrel slidable through the screw-block and the stationary head to enter the tube, a head movable in the tube and mounted on the inner end of the mandrel, said heads

forming a chamber in the tube, means for charging fluid-pressure into said chamber, and a series of sleeves displaceably mounted on the outer end of the mandrel and interposed between abutments formed by the screw-block and a nut turned onto the outer extremity of the mandrel, said sleeves and abutments operating to hold the mandrel and movable head against the thrust of fluid-pressure in the chamber, the removal of the nut from the mandrel permitting sequential displacement of the sleeves from the mandrel with a consequent inward movement of the mandrel and movable head 15 when the chamber is charged with fluid-pressure, the sequential displacement of the sleeves from the mandrel controlling the advance of the movable head and the length of the individual sleeves determining the 20 area of increase in the consecutive applications of the fluid-pressure.

7. An apparatus for treating metallic tubes to shape and to strengthen the same, comprising a temporary closure for one end 25 of the tube to be treated, a head movable in the tube and forming with the temporary closure an extendible chamber, means for charging fluid-pressure into the chamber, a mandrel slidable through the temporary 30 closure into the tube and attached to the movable head to control the movement of said head, and a series of sleeves displaceably mounted on the mandrel outside of the tube and interposed between abutments on 35 the tube and the mandrel, said sleeves operating to control the inward movement of the mandrel.

8. An apparatus for treating metallic

tubes to shape and to strengthen the same, comprising a closure for one end of the tube 40 to be treated, a head movable in the tube and forming with said closure an extendible chamber, means for charging fluid-pressure into the chamber, a mandrel entering the tube and attached to the movable head to 45 control the movement of said head, and a series of sleeves displaceably mounted on the mandrel outside of the tube and interposed between abutments on the tube and the mandrel, said sleeves operating to control the 50 inward movement of the mandrel.

9. An apparatus for treating metallic tubes to shape and to strengthen the same, comprising a closure for one end of the tube 55 to be treated, a head movable in the tube and forming with said closure an extendible chamber, means for charging fluid-pressure into the chamber, a mandrel entering the tube and attached to the movable head to control the movement of said head, and a 60 series of sleeves displaceably mounted on the mandrel outside of the tube and interposed between abutments on the tube and the mandrel, said sleeves operating to control the inward movement of the mandrel, 65 each of said sleeves being divided longitudinally and provided with means to clamp the divided parts together so that said parts can be separated and the sleeve removed from the mandrel.

In testimony whereof I have signed this specification.

EUGENE SCHNEIDER.
